UNITED STATES PATENT OFFICE.

CHARLES E. DURYEA, OF PHILADELPHIA, PENNSYLVANIA, ASSIGNOR TO REO MOTOR CAR COMPANY, OF LANSING, MICHIGAN, A CORPORATION OF MICHIGAN.

COOLING SYSTEM.

Application filed January 18, 1919. Serial No. 270,350.

To all whom it may concern:

Be it known that I, CHARLES E. DURYEA, a citizen of the United States, residing at Philadelphia, county of Philadelphia, State 5 of Pennsylvania, have invented a certain new and useful Improvement in Cooling Systems, and declare the following to be a full, clear, and exact description of the same, such as will enable others skilled in 10 the art to which it pertains to make and use the same, reference being had to the accompanying drawings, which form a part of this specification.

My invention relates to cooling systems 15 and a special object of my improvements is to provide an improved means for automatically regulating the cooling of automobile engines.

I secure this object in the device illustrated in the accompanying drawings in which:

Figure 1 is a front elevation of an automobile radiator partly broken away to show the interior construction thereof and adjacent parts embodying my invention.

Figure 2 is a sectional plan view of the same.

Figure 3 is a detail sectional view of a portion of said radiator and attached parts 30 to an enlarged scale.

Figure 4 is a view similar to Fig. 3 showing the parts in a different position.

Figure 5 is a vertical sectional view to a somewhat enlarged scale of the radiator 35 and adjacent parts shown in Fig. 1 and also showing the fan in its relative position.

Figure 6 is a detail sectional plan view 40 showing the adjustable pawl by which the blinds may be held in an approximately closed position.

a is the frame, or casing, of the radiator. *b* indicates blind slats of the kind commonly called Venetian blinds. These slats are pivoted eccentrically as shown and have 45 their pivotal axes vertical. The pivots are indicated by the reference character *b*² and consists of vertical stationary pintles extending upward into apertures in the lower end of the blinds. This construction does 50 not permit the accumulation of water at the joints which might prevent their operation. *e* is a rod pivotally attached to each of the blinds *b* at the same distance eccentrically from its pivot. By moving the rod *e* in the 55 direction of its length all the blinds *b* are

simultaneously turned about their pivots *b*². *f* (Fig. 2) is a tension spring acting to draw the rod *e* toward the closed position of the blinds *b*. *d* is the core, or cooling surface, of the radiator.

c is the fan by which the cooling current of air is actuated to cause it to pass thru and over the cooling surface *d*. Of course the motion of the vehicle will also cause a current of the air to pass thru and over 65 said cooling surface.

*h*³ is the blade of a vane having a considerable surface and interposed in the path of the current of air passing thru and over the cooling surface *d*. This blade is pivoted 70 at *h*² on a vertical pivot and extends to the other side of said pivot in an arm *h*. *g* is a connecting rod pivoted at one end to the outer end of the arm *h* and at the other end to an eccentric point on one of the blinds *b* 75 at the end of the series of blinds. *b*³ is a finger extending from the blind to which the rod *g* is pivoted. *i* is a stop adjustable in length by means of an adjusting screw *k* (Fig. 6). The stop *i* is flexible and adapted 80 to be moved laterally to interpose its end in the line of travel of the finger *b*³, as shown in Fig. 4, to hold the blinds *b* in their approximately closed position or to be withdrawn therefrom, as shown in Fig. 3, so 85 that the blinds are free to move about their pivots *b*². *j* is a thermostatic strip having its outer end connected by a rod *j*² to the stop *i*. The strip *j* is fastened to the casing of the radiator, or in some position so that 90 it will be subjected to the heat of the radiator.

The construction and arrangement of the parts just described is such that when the radiator is cold the stop *i* will be interposed 95 in the travel of the finger *b*³ and hold the blinds *b* in their approximately closed position. When the temperature of the radiator rises the strip *j* will be moved to draw the stop *i* out of line of travel of the finger *b*³ 100 so as to permit of the turning of the blinds about their pivots. The stop *i* itself may be made of thermostatic metal and so located as to be subjected to the temperature of the radiator if desired.

The operation of the above described device is as follows:

When the radiator is cold and the engine started up the blinds *b* are held nearly closed until the temperature of the cooling water 110

5 rises and causes the thermostat to withdraw the stop *i* from the line of travel of the finger *b*⁸. The current of air, or difference of air pressure, caused by the fan *c* or the motion of the vehicle acts upon the slats *b* to turn them from their approximately closed position and the air passing thru between said slats and thru the cooling surface strikes against the vane blade *k*³ 10 turning the vane about its pivot *h*² and by means of the rod *g* actuating the blinds *b* to their furthest open position and holding them in this position as long as the current of air is passing.

15 When the engine and vehicle stop the current and pressure of air no longer acts upon the blinds and vane and the spring *f* draws the slats toward their closed position. If the engine and parts remain at rest until 20 the radiator cools down the slats are held in this position by the stop *i* but if the engine is started up before the radiator cools down the slats are again immediately automatically opened as above described.

25 By turning the screw *k* the stop *i* may be adjusted in length so as to limit the opening movement of the blinds to the position desired.

30 *g*² is a set screw for limiting the open travel of the blinds under all conditions, and *x* is a similar set screw for preventing the complete closure of the blinds.

What I claim is:

1. In an apparatus of the kind described, 35 the combination of a fan, adapted to be driven by the engine at a speed proportional to that of the engine, a radiator, said fan being adapted to propel a current of air over the cooling surface of said radiator, 40 a damper arrangement adapted to control the area of passage for the cooling air, a pivoted vane located in the current of air produced by said fan upon the same side of said damper as said fan, said vane being 45 connected with said damper so that it shall actuate the same to vary the area of passage for the cooling air.

2. In an apparatus of the kind described, 50 the combination of a fan, adapted to be driven by the engine at a speed proportional to that of the engine, a radiator, said fan being adapted to propel a current of air over the cooling surface of said radiator, a damper arrangement adapted to control the 55 area of passage for the cooling air, a pivoted vane located in the current of air produced by said fan upon the same side of said damper as said fan, said vane being connected with said damper so that it shall 60 actuate the same to vary the area of passage for the cooling air, means for automatically actuating said damper towards its closed position and an adjustable stop to limit the closing motion of said damper.

3. The combination with a radiator having 65 a cooling surface, a damper adapted to regulate the area of passage for the cooling air, said damper being adapted to be actuated by the pressure of the air, means for restraining the movement of said damper, said restraining means being adapted to be automatically withdrawn from its operative position.

4. The combination with a radiator having a cooling surface, a damper adapted to regulate the area of passage for the cooling air, 75 said damper being adapted to be actuated by the pressure of the air, means for restraining the movement of said damper, said restraining means being adapted to be automatically withdrawn from its operative position, 80 by heat imparted from said radiator.

5. The combination with a radiator having a cooling surface, a damper for adjusting the area of passage for the cooling air, 85 said damper being adapted to be forced to its open position by an air current, a spring actuating said damper towards its closed position, a vane interposed in the line of travel of the cooling air, said vane being connected with said damper to open the same 90 and a detent adapted to hold said damper in a position slightly removed from its closed position.

6. The combination with a radiator having a cooling surface, a damper for adjusting 95 the area of passage for the cooling air, said damper being adapted to be forced to its open position by an air current, a spring 100 actuating said damper towards its closed position, a vane interposed in the line of travel of the cooling air, said vane being connected with said damper to open the same and a detent adapted to hold said damper 105 in a position slightly removed from its closed position; means for adjusting said detent for the purpose described.

7. The combination with a radiator having a cooling surface, a damper for adjusting the area of passage for the cooling air, 110 said damper being adapted to be forced to its open position by an air current, a spring actuating said damper towards its closed position, a vane interposed in the line of travel of the cooling air, said vane being connected with said damper to open the same 115 and a detent adapted to hold said damper in a position slightly removed from its closed position, and a thermostatic means subject to the heat of the radiator for withdrawing said detent from its operative position.

8. In an apparatus of the kind described, 120 a blind having a vertical axis, a socket on the lower end of said blind, a stationary pintel located below said blind and extending upwardly into said socket, substantially as and for the purpose described.

9. The combination with an automobile of

a radiator located at the front thereof and consisting of a passage for air and cooling surface in said passage, a blind adapted to substantially close said passage and to open 5 the same, said blind being pivoted eccentrically and arranged so as to be opened by the pressure of the air against said blind, and

a spring yieldingly tending to close said blind, and a stop adapted to automatically prevent the complete closure of said blind. 10

In testimony whereof, I sign this specification.

CHARLES E. DURYEA.
